W. M. TAPLIN.

SASH FASTENER.

APPLICATION FILED FEB. 7, 1921.

1,391,429.

Patented Sept. 20, 1921.

FIG. 4

INVENTOR:

WILLIAM M. TAPLIN

BY
John C. Higgins
ATTORNEY.

UNITED STATES PATENT OFFICE

WILLIAM M. TAPLIN, OF ST. LOUIS, MISSOURI, ASSIGNOR OF ONE-HALF TO CHARLES SCHROEDER, OF ST. LOUIS, MISSOURI.

SASH-FASTERNER.

1,391,429.

Specification of Letters Patent. Patented Sept. 20, 1921.

Application filed February 7, 1921. Serial No. 443,205.

To all whom it may concern:

Be it known that I, WILLIAM M. TAPLIN, a citizen of the United States, and resident of St. Louis, Missouri, have invented certain new and useful Improvements in Sash-Fasteners, of which the following is a specification containing a full, clear, and exact description, reference being had to the accompanying drawings, forming a part thereof.

My invention relates to an improved adjustable burglar-proof window-ventilating sash-fastener, and it consists in the novel construction and arrangement of parts hereinafter described, and distinctly pointed out in the claim found at the end of this specification.

The object of my invention is to provide an improved device for adjustably locking together the sashes of windows, to make the windows practically burglar-proof, and yet permit the sash to be partly or fully opened for purposes of ventilation; and which will be of very low cost in manufacturing and attaching the lock, owing to the simplicity and ease of application thereof.

In the drawings—

Figure 1 is a horizontal fragmentary section of a window and the sash thereof, having my invention applied thereto; the section being taken on the line 1—1 of Fig. 2.

Fig. 2 is an inside front elevation of a portion of a window and the sash thereof, illustrating the same parts that are shown in Fig. 1.

Fig. 3 is an enlarged detail vertical section, taken on the line 3—3 of Fig. 2, and

Fig. 4 is an enlarged (or rather a full-sized) detail plan-view of the clamping-bracket, detached.

The numeral 1 designates the window-frame, in which are arranged the usual sashes having the horizontal meeting-rails 2 and 3, vertical side-rails, and (in some cases as here shown) a vertical center-rail 4 which separates the glass.

Fixed to the lower portion of the said vertical center-rail 4, or to the lower portion of one of the side-rails of the sash, and extending upwardly a suitable distance, above the meeting-rail 2 of the upper sash, is a vertical locking-plate 5.

Said locking-plate 5 is provided upon its back with a series of lugs or projections 6, and a tapered or conical perforation 7 ex-

tends through said plate and through each of said lugs.

Said locking-plate 5 is secured to the sash by means of common screws 8, which pass through said conical perforations 7 in both plate and the lugs 6, and engage the sash, as shown more clearly in Fig. 3.

Said lugs 6 act as spacers, to hold said plate 5 a distance away from the vertical sash-bar 4, and permit the action hereinafter described.

The locking-plate 5 is provided with a vertical row of horizontal serrations, or is knurled, or otherwise made rough at 9, leaving the edges of said plate smooth, so that said edges may freely slide in the space 10 between the body 11 and the integral opposite overhanging clamping-jaws 12 of a clamping-bracket.

Said clamping-bracket 11 is secured to the upper side of the meeting-rail 3 of the lower sash, by means of screws 14 passed through countersunk perforations 15 formed in said bracket, so that when the sashes are adjusted up or down the said locking-plate 5 may move freely in the said space 10 between the body of the bracket and said clamping-jaws 12 thereof, past the projecting spacing-lugs 6 and screws 8, and run out of said space and off of said bracket, whenever the sashes are opened a greater distance than the length of said locking-plate.

A horizontal integral boss 16 is formed upon the upper side of the said clamping-bracket 11, and a long thumb-screw 17 is threaded completely through the said boss, as well as through the body of said bracket, so that the attenuated inner end of said thumb-screw will engage said serrations 9 of said locking-plate 5, in locking the two sashes together.

By tightening the said thumb-screw 17, the sashes will be securely locked together, and it will be impossible for a burglar to move the sash and enter the house when said thumb-screw is firmly set against the said serrations 9 of the locking-plate 5, without breaking in; and yet suitable ventilation may be provided by raising the lower sash (or by lowering the upper sash) a slight distance, and then locking them together, as described.

The operation and use of my improved sash-lock will be readily apparent from the above description.

I claim:—

The improved sash-fastener, comprising a clamping-bracket having integral opposite jaws with a spacing-lug-passage between 5 themselves, and there being a locking-plate space between said jaws and the adjacent inner end of said bracket; means for securing said bracket to the meeting-rail of a sash; a vertical sliding locking-plate provided on its 10 back with a series of spacing lugs, there being tapered perforations through the latter and through said plate, the said lugs being arranged to act as spacers to hold said plate a distance from the vertical sash-bar to 15 which it is attached, and thereby permit said lugs to pass up and down in the said spacing-lug-passage between said opposite jaws of

said clamping-bracket; screws for securing the said plate to the sash; and a thumb-screw 20 threaded horizontally through the body of said clamping-bracket, the inner end of said thumb-screw being attenuated, to engage said locking-plate and force the same into contact with said opposite jaws of said clamping-bracket, and lock said plate in the 25 space between said jaws and the body of the clamping-bracket.

In testimony whereof, I have signed my name to this specification in presence of two subscribing witnesses.

WILLIAM M. TAPLIN.
